[57] CLAIM

The ornamental design for a limited access ratchet wrench, as shown and described.

DESCRIPTION

FIG. 1 is a top perspective view of the limited access ratchet wrench showing my new design, the handle being shown in broken lines for illustrative purposes only and forming no part of the claimed design;

FIG. 2 is a bottom plan view thereof;

FIG. 3 is a side elevational view thereof, the opposite side being a mirror image;

FIG. 4 is a front elevational view thereof;

FIG. 5 is a rear elevational view thereof;

FIG. 6 is a bottom plan view thereof showing the shank in the angularly offset position;

FIG. 7 is a top plan view of the limited access ratchet wrench showing a second embodiment of my new design; and

FIG. 8 is a top plan view of limited access ratchet wrench showing a third embodiment of my new design. The shank is shown broken away in FIGS. 7 and 8 for ease of illustration only.
